US0D1104959S

(12) **United States Design Patent** (10) **Patent No.:** **US D1,104,959 S**
(45) **Date of Patent:** **** Dec. 9, 2025**

(54) **BATTERY CHARGER**

(71) Applicant: **Kodai Industries Ltd**, Guangdong (CN)

(72) Inventor: **Tiankun Xu**, Hong Kong (CN)

(73) Assignee: **Kodai Industries Ltd**, Shenzhen (CN)

(**) Term: **15 Years**

(21) Appl. No.: **29/967,663**

(22) Filed: **Oct. 11, 2024**

(51) LOC (15) Cl. **13-02**

(52) U.S. Cl.

USPC **D13/107**

(58) **Field of Classification Search**

USPC **D13/107, 108, 110, 118, 119**

CLAIM

The ornamental design for a battery charger as shown and described.

DESCRIPTION

FIG. 1 is a perspective view of a battery charger showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the battery charger and form no part of the claimed design.

1 Claim, 8 Drawing Sheets
